UNITED STATES PATENT OFFICE.

SOCRATES A. XIPPAS, OF PITTSBURGH, PENNSYLVANIA.

ELECTRIC FAN.

Application filed August 14, 1924. Serial No. 731,991.

REISSUED

To all whom it may concern:

Be it known that I, SOCRATES A. XIPPAS, a citizen of the United States, residing at Pittsburgh, in the county of Allegheny and State of Pennsylvania, have invented certain new and useful Improvements in Electric Fans, of which the following is a specification.

- 10 My invention relates to electric fans. The object of the invention is to provide a device which will produce a large amount of air blast and to have no visible moving parts which renders the fan absolutely safe against accidents.
- 15 A further object of the invention is to provide a device which will cause a continuous flow of air in all directions and to take the place of the ordinary "buzz" oscillating fans and their crude and intricate mechanism as 20 in my invention there are only two bearings and no interior working parts liable to get out of order.
- 25 A further object is to provide means whereby the blast may be regulated so as to blow in any one or more particular directions when it is not desired to have the blast to discharge in all directions, which directions includes vertically, horizontally and any angle of blast discharge 30 between the points designated.
- 35 Further objects and advantages will be more fully described herein and specifically pointed out in the claims hereunto annexed recourse being had to the accompanying drawings forming a part of this specification in which:—
- Figure 1 is a view of the complete fan.
- Figure 2 is a view of the upper portion of the fan showing the blast regulating or cut off plates on the perforated casing or sphere.
- 40 Figure 3 is a perspective view of one of the blast shut off or cut out plates.
- Figure 4 is an edge view of the obliquely or angularly disposed rotary disc showing 45 two depending blades or wings in side elevation.
- Figure 5 is a plan of the obliquely mounted ring showing an edge view of the wings or blades.
- 50 Figure 6 is the same as Figure 4 but showing two wings or blades in side elevation above the ring or oblique disc.
- Figure 7 is a perspective view of the oblique annulus or ring with its wings or impellers.
- 55 Figure 8 is a fragmentary cross section of a part of the upper section of the spherical fan cage showing the bearing for the upper portion of the rotary vertical shaft, and Figure 9 is an elevation of a portion of the vertical shaft showing the two part hub or centre of the rotary wing mechanism or rotor and the bevel or angular ends of the same.
- 60 In the drawings like reference numerals indicate similar parts in all the several views:—
- 65 Referring to Figure 1, 1 is the base or stand of the apparatus arranged in the ordinary manner.
- 70 2 is a vertical motor adapted to have a vertical shaft, also, and to drive the hereinafter described rotor with its wings or impellers.
- 75 3 are the brush terminals of the motor and are adapted to be attached to wires leading to an electric supply.
- 80 4 are the lubricating oil cups, and 5 is the vertical motor shaft before mentioned.
- 85 6 is a switch, Figure 1, for regulating the speed of the motor in the usual manner.
- 90 Mounted on the upper end of the motor 2 is a spherical perforated cage or shell entirely enclosing the hereinafter described wing or impeller mechanism which constitutes the blast making fan or rotor, and is in two parts, the upper 7 and the lower portion 8 suitably united as at 7^a, in Figure 1.
- 95 The shaft 5 passes through the sphere or globe 7—8, its lower end being suitably mounted for rotation in the step bearing 9, dotted lines, the upper end of the shaft rotates in the bearing 10 in the top portion 7 of the perforated cage or spherical shell.
- 100 11 is an ornament, said ornament also forming points of attachment for the hereinafter described shut off plates.
- 105 In order to permit the blast to be discharged from the perforated globe shaped cage or shell, the perforations 12 are cut therein and are arranged radially from the top of the cage downwards to near the centre 7^a and covers the entire surface.
- 110 The perforations 12 vary in width and increase as they approach the centre 7^a of the globe 7—8.
- 115 It will be seen that the perforations permit the blast to be freely discharged from the entire surface, upwards, downwards and at any inclination.
- 120 13 are perforations or blast orifices formed by the belt or horizontal bars 13^a and the radial staggered bridge bars 13^b.

thus forming elongated or rectangular blast exit passages.

As shown in Figure 1, two kinds of perforations are placed on the sphere or globe 5 but the entire surface of the ball like cage may be perforated with only one style, that is, either the radial spaces 12 or the girth or horizontal slots 13.

Upon the shaft 5 at or near the central 10 portion of the cage, globe or sphere 7-8, is placed a sleeve or collar 14 having an angular or bevelled portion 16.

15 is a similar sleeve or collar having a bevelled end 16 corresponding to the bevel 15 of the sleeve 14.

Both sleeves are secured to the shaft 5 by the set screws 17 and are adapted to be separated a short distance so as to form a space for the clamping of the centre 18 of 20 the ring or annulus 19. Therefore, when said centre 18 of the ring or gyrator 19 is firmly clamped by the parts 14 and 15 forming a collar, the ring is held at an angle, (Figures 4 and 6), or in an oblique position, 25 as shown. In order to form the ring 19, a disc of metal is cut so as to form a series of blades, wings or impellers, usually four, and to accomplish this, the circular disc is cut into four parts which are bent upwards 30 and downwards to form the blades 20.

The cut out segments above mentioned are smaller than the actual segments capable of being cut from the circular disc thus producing the spokes or arms 20^b, Figures 35 5 and 7.

Two of the blades are bent upwards and two bent downwards, as shown, and the blades are preferably made to assume slight angles to each other.

40 Referring to Figures 4 and 6, it will be seen that the outer peripheries 21, shown by dotted lines, of the upper wings or blades 20 form a circle as do the lower blades or wings, Figure 4, therefore they form a portion of two discs intersecting each other at right angles.

The manner of operation involving the oblique or wabble motion of the ring 19 and its blades or wings 20 is, that by the peculiar 50 motion of the rotating parts, the air is forced upwards upon the rising of the ring to its highest position and forced downwards by the lower blades and the alternate and rapid reversals of motion forces a large 55 quantity of air in all directions.

In this invention there is more blast for less blade area as the air is slightly compressed or retarded and then discharged there being no ineffective or dead surfaces 60 as is common in fans of the propeller disc variety.

In order to provide means whereby the blast may be directed or restricted to a certain direction I provide shutters or cut off plates 65 22 and 23 conforming in shape to one

eighth, more or less, of the surface of the sphere or globe enclosure 7-8, Figures 2 and 3. The plates are provided with rings 24 at their upper or lower portions the eye or hole of which are adapted to be inserted 70 over the boss 25 and the portion 26, Figure 1.

In this manner the plates 22 and 23 can be rotated entirely around all portions of the sphere 7-8 so that a certain number of 75 the perforations 12 and 13 can be closed or cut out and the blast of air directed at a given point or points at will.

The plates for convenience, are provided with knobs 27 for facilitating the movement 80 thereof.

In the fan described, the motor by which the beforementioned wings or blades are driven, is vertical so that it is not necessary for the motor to assume any angular position as is done in the ordinary disc or "buzz" 85 fan and which is effective only in small areas. The uses of my invention are more varied than the ordinary propeller fan and is better suited for commercial uses besides 90 being absolutely safe where there are children as there is no danger of severed or injured fingers.

For drying ladies' hair after shampooing, the fan can be held close to or against the 95 head without inconvenience or danger and have the blast to blow in all directions.

At dining tables, lunch counters and other places, the blast is directed to each 100 person alike and eliminates flies for a large area around said tables or counters.

In the directing of the blast upwards, downwards as well as at all angles, the quiescent heated air at the ceiling of a room is dislodged and permits the circulation of 105 fresh air.

The amount of electric current required to operate my device is less than that required for the ordinary type of fan to produce a greater amount of effective blast. 110

I may dispense with the angular positioning of the fan or blast element and place it at right angles to the axis of rotation.

I claim:—

1. An electric fan or blower, comprising 115 a motor shaft, and a disc mounted axially and obliquely thereon for rotation having wings or impellers, bent at right angles to each other.

2. An electric fan, a motor shaft, and a 120 circular disc axially mounted for rotation thereon and affixed thereupon at an angle, said disc provided with wings or blades at right angles thereto.

3. An electric fan, of a motor shaft, and an inclined horizontally positioned circular disc adapted to oscillate during a revolution, and blades or wings at right angles thereto. 125

4. An electric fan, of a rotary shaft, a circular disc horizontally mounted thereon 130

adapted to have a wabbling motion, and inclined wings or blades stamped from said disc.

5. An electric fan, of a motor shaft, a rotary disc mounted thereupon, said disc having sets of blades or blast wings formed thereupon oppositely disposed from each other and stamped from the disc to form an annulus or ring and radial bars or spokes 10 for supporting said blades.

6. An electric fan, a motor shaft, an obliquely mounted circular disc adapted to have a wabbling motion imparted to it by said shaft and having wings or blades bent 15 upwards and downwards formed from said disc and a connecting ring at the outer periphery of the blades and forming part thereof.

7. An electric fan, a motor shaft, a disc 20 disposed upon the shaft having kerfs cut to form segmental wings or blades when bent upward and downward, said wings being oppositely disposed and forming a supporting ring formed with said wings and connecting 25 the same at their peripheries.

8. An electric fan, comprising a circular disc having oppositely disposed impellers or blast producers and a supporting annulus cut and bent from said disc and mounted 30 within a spherical cage or shell provided with blast orifices and completely enclosing said blast means.

9. An electric fan or air distributor, comprising a wind blast creating winged circular disc and its inherent annulus or ring 35 arranged for rotary motion, an enclosure therefor having the form of a hollow ball or

sphere, said sphere being provided with orifices for the entrance and exit of the air blast and covering the entire surface of said 40 spherical enclosure.

10. An electric fan, comprising a series of circular conforming blast sectors at right angles to each other and formed from a circular disc, and a two part cage or globular 45 confining means therefor provided with blast outlets upon its entire surface for forcing the air in multiple channels and in every direction.

11. An electric fan, comprising a rotary 50 angularly mounted blast wheel or impeller formed of a single circular disc, a spherical cage or enclosure surrounding said wheel or rotor, said cage provided with blast outlets or orifices for directing the blast in every 55 direction.

12. An electric fan, comprising a rotary blast device, a perforated spherical or shell for confining the same, and a slidable plate or plates thereon conforming to the shape of the surface of said shell for opening and closing any number of said perforations at will to direct the blast in any particular direction.

13. An electric fan, comprising a rotary 60 blast wheel formed from a circular disc, a perforated spherical or globe shaped enclosure therefor, and circumferential plates adapted to be moved to cover and uncover any portion of the perforated surface of said spherical enclosure.

In testimony whereof I have hereunto affixed my signature.

SOCRATES A. XIPPAS.
